US00D879282S

(12) **United States Design Patent** (10) **Patent No.:** **US D879,282 S**
Noble et al. (45) **Date of Patent:** **** Mar. 24, 2020**

- (54) **FAN**
(71) Applicant: **DELTA T, LLC**, Lexington, KY (US)
(72) Inventors: **Ernest John Noble**, Selangor (MY); **Ken Siong Tan**, Selangor (MY); **Jon Jet Ling**, Selangor (MY); **Seng Rui Chan**, Selangor (MY)
(73) Assignee: **DELTA T, LLC**, Lexington, KY (US)
(***) Term: **15 Years**

(21) Appl. No.: **29/706,103**(22) Filed: **Sep. 18, 2019****Related U.S. Application Data**

- (63) Continuation of application No. 29/688,076, filed on Apr. 18, 2019, which is a continuation of application No. 29/633,558, filed on Jan. 15, 2018, now Pat. No. Des. 849,925, which is a continuation of application No. 29/562,520, filed on Apr. 26, 2016, now Pat. No. Des. 808,004, which is a continuation of application No. 29/531,907, filed on Jun. 30, 2015, now Pat. No. Des. 770,027.
- (51) **LOC (12) Cl.** **23-04**
(52) **U.S. Cl.**
USPC **D23/377**
- (58) **Field of Classification Search**
USPC D23/377, 413
See application file for complete search history.
